UNITED STATES PATENT OFFICE.

EBENEZER WRIGHT, OF LONDON, ENGLAND.

TYPE-WRITING AND MATRIX-MAKING MACHINE.

SPECIFICATION forming part of Letters Patent No. 440,086, dated November 4, 1890.

Application filed April 28, 1885. Serial No. 163,725. (No model.)

To all whom it may concern:

Be it known that I, EBENEZER WRIGHT, a subject of the Queen of Great Britain, residing at London, England, have invented a new and useful Improvement in Type-Writing and Type-Matrix-Making Machines, of which the following is a specification.

This invention will be best understood by reference to the accompanying drawings, in which like letters of reference represent like parts.

Figure 1 is a sectional side view of the mechanism for setting the type, shown when at rest. Fig. 2 is a like view, but with the key depressed as in use. Fig. 3 is a front view showing the type-bars, perforated plate, &c. Fig. 4 is a front view showing the traveler. Fig. 5 is a side view showing the printing apparatus. This view is taken from the opposite side to that shown in Figs. 1 and 2. Fig. 6 is a plan showing part of the key-board. Fig. 7 is a plan of part of the traveler, showing the guard W. Fig. 8 is a view of the segment-wheel O' and ratchet-gear from the side. Fig. 9 is a detail of the traveler-escape mechanism on an enlarged scale. Fig. 10 is a detached view of one of the type-bars G. Fig. 11 is a small view of the plate Q. Figs. 12, 13, and 14 are views of a different form of type-bar and type-supporting arms.

The letter A denotes a fixed frame-work wherever it appears.

B' are the keys of hexagonal shape, as shown, so as to permit of their lying very closely adjacent to each other, in order that in working a machine the operator's hand may have to travel as short a distance as possible from one key to another. These keys B' are separated by the thin dividing frame-work

B², so that two keys may not be depressed at the same time.

B are the key-bars, fulcrumed at B³, to which the keys B' are attached in any convenient manner, as by wires B⁴. There are as many key-bars B as keys B', and the back end of each is kept down and the front end up by a spring B⁵. The back end of the key-bar B lies underneath the sticker C. Angle-slots C' are provided, as shown in each of the stickers, (of which there is one to each key-

bar B,) and rods C², extending from frame to frame, pass through the slots C' and support the whole of the stickers C. A spring C³ or an equivalent device serves to keep the sticker pressed down. A pin or projection C⁴, pressed forward by the spring C⁵, passes through a hole in the sticker. Its end, extending forward under the rocking bar D, (of which there is one to each key-bar B,) is beveled on its under side to facilitate its passing D as the sticker falls after having been lifted.

The rocking bar D extends across the instrument from frame to frame and is journaled at each end. The upper edge of the rocking bar D rests against the end of the shooting-bolt E, (of which there is one to each key-bar B, though only a few are shown in the drawings,) which is kept pressed back against it by a spring E², Fig. 7. The shooting-bolt is guided in any suitable manner, as by the screw-pins E'.

Facing the front end of the shooting-bolt E is the pin F', which is free to slide in a hole in the perforated plate F. This pin F' is headed, so that it may not pass through the plate F.

An india-rubber spring F², by preference a piece of tubing divided longitudinally, is passed across the machine between each row of pins F', so as to prevent their sliding too freely or falling out altogether. To facilitate this the perforated plate F may be made of two thin plates with the rubber springs between, as shown in Fig. 1 of the drawings.

G is the type-bar, which bears upon its face in a long row the whole of the letters, figures, or other symbols. Each bar bears the same symbols, and the number of type-bars decides the number of symbols that can be printed in one line.

The type-bar G is forked or divided, as shown in Figs. 1 and 10, and fits upon the plate X, which extends across the instrument from side to side, upon which it is free to slide up and down, the guides Y, which extend from the face of the plate X and occupy the hollow space in the body of the type-bar, keeping it from swinging sidewise. The foot X' slides in a groove in the perforated plate. The descent of the bar may be regulated by the spring Z, whose pressure upon the bar is

regulated by the screw Z'. The object of this is to cause the bar to descend steadily and prevent lateral play, although it is obvious that equivalent and well-known means 5 may be employed to accomplish the same end. Fig. 10 shows one of these type-bars in elevation and plan.

The description so far will be best understood by reference to Figs. 1 and 3, and I will 10 now proceed to explain the action of the parts already described before proceeding with fresh details.

It must be understood that the object to be attained is to dispose the type-bars G in such 15 manner that the requisite letters, &c., shall be arranged consecutively along the printing-line, and this is accomplished by dropping the type-bars until the requisite letter comes opposite the printing-line. Thus, if one commences with the word "The," the first type-bar must drop until the letter "T" is on the printing-line, the second "H," and the third "E," and so on until the whole line is set. The proper key B' being depressed, the back end 20 of the key-bar B is raised and lifts the sticker C, which, on account of the angle-slots C' and rods C², does not rise quite vertically, but partly vertically and partly backward at about an angle of forty-five degrees with the vertical line. As C rises the end of pin C⁴ catches the 25 rocking bar D and turns it in its bearings, as shown in Fig. 2, while its other edge pushes forward the shooting-bolt E, which in its turn presses the pin F' through the perforated plate F, its end then projecting through sufficiently far to catch the type-bar G when 30 it falls. This being accomplished, upon still further depressing the key B', the pin C⁴ is, by the backward motion of the sticker C, drawn clear of the rocking bar D, when the 35 shooting-bolt E, under the influence of its spring, immediately returns to its original position, as in Fig. 1, carrying the rocking bar D also back to its former position. When 40 the key is released, the sticker C returns, the spring C⁵ yielding and allowing pin C⁴ to slide back, so as to pass the rocking bar D, the end of the pin, as already explained, being beveled to facilitate this. Now, say there are 45 thirty-five symbols upon each type-bar G, there will be a like number of pins F' in a 50 vertical line underneath it, so as to arrest the bar at the right place to bring any one of the thirty-five symbols opposite the printing-line. There will also be thirty-five shooting-bolts E, one to each pin F'. Say the instrument is to print thirty letters in a line, there will then be thirty type-bars G arranged 55 side by side, and under each bar will be the row of thirty-five pins F'. There would thus be one thousand and fifty pins and a like 60 number of holes in the perforated plate F. (See Fig. 3, where, however, only a portion of the holes are shown.)

65 Having thus described how the type-bars G are arrested at their proper places, I will now proceed to explain how the bars G are sup-

ported and caused to drop, as required. In an instrument having thirty-five symbols upon each bar, there would only be thirty-five shooting-bolts E, as these are arranged upon a traveler H, which travels horizontally across the instrument, so that the bolts E come successively opposite each row of pins F', and so command the whole number. The 75 depression of a key B' moves the traveler and bolts E the exact distance from one vertical row of pins F' to the next row. It is because the bolts E traverse the instrument that the rocking bars D extend the whole way across 80 it, so as to operate the bolts, no matter in what position they may happen to be.

The traveler H is shown in front elevation in Fig. 4, and consists of an upright H, traversing the guide-rods H' upon pulleys or runners H², which bear upon the rods H'. As already stated, this traveler moves the distance of one row of pins F' every time a key is depressed, and this is accomplished by the spring-wheel I, which contains a watch-spring 85 and to the periphery of which is attached the cord J, which is wound upon the wheel I by the power of the spring as the traveler H travels toward it. The cord J passes vertically to the pulley J', and thence horizontally 90 to the traveler, to which it is secured at J². The traveler H has therefore a tendency to move in the direction indicated by the arrow, but is prevented from going by the ratchet-bar H³, the teeth of which engage with the escapement mechanism shown on a larger scale 95 in Fig. 9, which shows the bar just moving. The two rows of teeth on the ratchet-bar H³ are arranged alternately, or so as to "break point" with each other, and in the normal position the upper escapement K' is in gear with 100 a tooth of the upper side of the bar. When a key B' is depressed, it forces down the front end of the escapement-lever L, Fig. 1, and so raises its back end, which is jointed to the 105 vertical rod K³, Fig. 4. The escapement-lever L extends across the instrument under the whole of the keys, so that whatever key be depressed the lever is operated. The end of 110 this rod is just clear of the escapement K; but as it rises it pushes this up, disengaging the pallet K', and placing the pallet K² in position 115 to stop the next tooth on the lower side of the bar. The traveler has now moved about half the distance it has to go to come right for the 120 next row of pins F'. Upon the key being released the rod K³ falls and the spring K⁴ draws down the escapement K, thus releasing 125 pallet K², when the traveler at once moves forward until stopped by the pallet K' engaging with the next upper tooth of bar H³. This operation is repeated every time a key 130 is depressed. The return motion may be arranged for in any convenient manner, and calls for no special description.

The traveler H has an arm H⁴, which carries the runner H⁵, Figs. 1, 2, and 4, and this runner as it passes raises the tails of the detents M, which hold up the type-bars G, which 135

consequently drop down until stopped by their respective pins F' , as already explained. In Fig. 1 the runner H^5 is just ready to lift the detent M and the type-bar G is still held up. In Fig. 2 the action has taken place and the type-bar has dropped and is seen resting upon the pin F' .

In practice the release of the type-bar should be effected after the projection of the pin, so as to allow time for correcting an error—such as touching the wrong key—which is often done involuntarily and detected instantly, but too late to stop depressing the wrong key.

I have so far described the key-board and its mechanism for shooting the pins F' , which settle the position of the type-bars G when dropped; also the mechanism for supporting the type-bars and the traveler, which releases the type-bars and the means by which the traveler is operated.

I will now describe the printing mechanism, which will be best understood by reference to Fig. 5. It will be remembered that the type-bars are all dropped, so that the required letters or symbols are set in one horizontal line, which I call the "printing-line." The paper P is carried upon the endless band N , which is carried upon the two rollers N' and N^2 , which form part of the swing-frame N^3 , which is capable of swinging upon the spindle of the top roller N' as a center. The paper is secured upon the band N by any suitable form of clip N^4 . One end of the cord n is fastened at N^5 to the swing-frame N^3 and from thence passes over the runner n' round the cord-wheel O , to which it is fastened, up again, and over the other runner n^2 , its other end being fastened to the arm N^6 , as shown. If now the wheel O be turned by any convenient handle in the direction of the arrow, it will cause the swing-frame to approach the type-bar. To prevent the paper P from touching the type-bars anywhere except upon the printing-lines, a thin plate Q^x is provided and pivoted at Q' , and has a long slot Q^2 , through which the printing takes place. The swing-frame N^3 and the plate Q^x work upon different centers, which are so related that when the swing-frame reaches the end of its travel to the type-bars the roller N^2 comes opposite the slot Q^2 and forces the paper against the type-bars, thus obtaining the impression.

Upon the end of the roller N^2 is the toothed wheel R , which, as the frame N^3 approaches the type-bars, gears with the rack R' upon the curved arm R^2 . This has the effect of traversing the endless band and paper, so as to bring the right part opposite the slot Q^2 to bring the right part opposite the slot Q^2 in the plate Q^x . As the frame N^3 returns, the wheel R is revolved in the opposite direction, so as to bring the paper back again to the front side of the roller, when the line just printed can be seen.

At each reciprocation of the swinging frame N the paper is fed forward a distance equal to that between two printed lines by any suit-

able or well-known feed mechanism, as, for instance, by the mechanism shown in Fig. 5, which consists of a pawl p , engaging a ratchet 7^0 on the shaft of the toothed wheel R behind the same, with which also engages a pawl p' , that holds the ratchet against reverse movement, or any other usual feed mechanism may be employed. Pawl p is mounted on a movable support held in adjusted position by a set-screw p^5 passing through the downwardly-turned end p^6 of the arm R^2 , whereby the feed of the paper may be regulated by causing the roller to rotate more or less, as will be readily understood. The three inking-rollers S are caused to descend over the face of the type-bars that have dropped into place, as the swing-frame approaches the type-bars, by means of the curved arms S' , of which there is one at each end of the swing-frame, and are guided by the slots S^2 . They have always a tendency to rise again under the influence of the helical spring S^3 .

A mirror T is so placed that the line of type can be inspected, and the symbols upon the type-bars G being placed upside down appear right way up in the mirror. The printing upon the paper is also right way up, as seen by the operator from the front, though it is upside down as printed. Beside the cord-wheel O is the segmental toothed wheel O' , (a back view of which is shown in Fig. 8,) free to revolve upon the shaft O^3 , but carried round with O by means of a pawl and ratchet-wheel 100 in the direction opposite to that of the arrow upon O . Thus as O moves in the direction of the arrow it has no effect upon the wheel O' ; but when it returns again it carries O' round with it. O' gears with the pinion U' , which is 105 fixed upon the shaft U^2 , which carries the cord-wheel U , so that as the wheel O returns to its normal position, after the printing-stroke has been made, the wheel U is revolved in the direction of the arrow and winds up the cord 110 U^3 , which passes round the runner U^4 at the bottom and the runner U^5 at the top of the instrument, and is finally connected to the roller and carriage V , (shown behind wheel O), which is thus drawn up across the face of 115 the perforated plate F , pushing in all the pins F' which have been projected in setting the line of type, and also pushing up those type-bars G which have been dropped back into their normal places, where they are caught 120 and held by the detents M , as previously explained. By the time the roller V has reached the end of its travel (the top of its stroke) one of the blank spaces upon the segment-wheel O' has reached pinion U' , which is 125 consequently released, and the roller and carriage V instantly descends again to its former position under the influence of its own weight and the spring V' , located at the upper back part of the instrument and connected with a 130 cord V^2 , which passes round the runner V^3 at the bottom, and is finally connected with roller V .

The number of blank spaces upon the

wheel O' is for convenience four, because the wheels O and O' are moved by the handle a quarter of a revolution each time. However, the number of spaces may be varied, if desired.

Where necessary to the proper working, the shafts are carried right across the instrument and the wheels, &c., repeated at the other side of the instrument. This occurs in such cases on the shafts O³ and U² and the wheels O and U; but to avoid confusion I have merely described these as applied to one side of the machine.

By throwing out of gear the wheel U, which may be effected by mounting the said wheel U in shifting bearings, preferably bearings in the end of the standards U^x, pivoted, as shown in Fig. 5, to the main frame, so as to permit the wheel and its pinion to be swung to one side, as will be readily understood, it is obvious that the type-bars will not be disturbed, and the line of type may be reinked and printed from as many times as desired. The utility of this for such purposes as addressing newspaper-wrappers, printing labels, &c., will be readily appreciated.

The guard W shown in Fig. 7 is for the purpose of protecting the points of the shooting-bolts E, as without such protection when the traveler H returned the bolts would be liable to catch against the heads of the pins F', (in case they had got started back, as by tilting the instrument backward, vibration, &c.) This guard is formed at an angle at W and W², so that the pins striking it on either side are returned to their correct position in plate F.

The mechanism for adapting my type writer for the formation of stereo-matrices is very simple, and is shown in Figs. 12, 13, and 14. It is obvious that for this purpose some means is required, first, whereby the line of type forming the printing-line can be projected beyond the level of the rest, so that the matrix can be impressed against it, and, second, whereby the difficulty caused by the differing width of letters can be obviated, and the letters themselves, whether thin or thick, brought into as close juxtaposition as if set up in the ordinary way. I effect both these purposes in the following manner:

The letters or symbols are removed from the type-bars G and placed upon the ends of the arms g, which are jointed to the type-bars G in any suitable manner, as at g', Fig. 14. In a horizontal line there is thus one arm g to each type-bar G, and in a vertical line there are as many arms as there are letters or symbols arranged one above the other, four of them being thus shown in Fig. 14. These arms g are hollow, and each contains a helical spring a, (which is always in a state of tension,) one end of which is secured in the hollow arm g and the other to the flat spring b, which carries the type c, upon which is the type-face d. The types c are thus connected with the type-bars G by an exceed-

ingly flexible connection, so that they can be drawn out, as at e, Fig. 12, so as to be clear of the remaining arms, &c., and compressed together, as in Fig. 13, while still keeping their sides parallel and the type even across the face, notwithstanding that some of the arms g have to be turned radially upon their pivots g', and the type of the outer arms are drawn out somewhat farther to bring them up to the face-level. A further spring, as a¹⁰, Fig. 14, will be necessary to bring each type-arm back to its original position after turning on its pivot; but a common spring for the whole of each vertical line of type-arms will suffice for this, the construction of such a spring being exactly similar to a¹⁰, save that instead of embracing a single arm it embraces the whole series.

Each type c is pierced with a hole c', so that a screw-rod h may be run through the whole of the types. When this has to be done, the whole of the types on the rod h are first drawn forward so as to be clear of those above and below. They are then pressed together at the sides until the vacant spaces caused by some letters being thinner than the rest, while the type-bars are necessarily of the maximum width, (see Fig. 12,) no longer exist, but the whole line of type presents as perfect an appearance as if set up in the usual way. Now comes the important operation of "justifying," a term universally used by printers to signify the adjusting of each line of type so that it may finish with a complete word or with a syllable followed by a hyphen. This can be easily accomplished in my machine in the following way: In the first place, the number of type-bars used will be somewhat in excess of the maximum number of letters likely to be required in any line. In printers' words the line when compressed will be somewhat wider than the measure in use. It may happen that the full width of the measure comes exactly at the end of a word. No justifying will then be required; or it may come in the middle of a word. In that case the operator must have a means of expanding or contracting the line set. For the first purpose he would only have to insert temporary wedges between the words, so as in effect to space more widely than usual. To effect the second purpose, I propose to make the quads K of india-rubber, or equivalent yielding and resilient body, so that they will yield to extra pressure on the sides. This would enable a few of the surplus letters to be got in the line—in other words, the line will be closely spaced. The same, of course, applies to the division of long words at a convenient syllable, only that a hyphen must then be inserted temporarily at the end of the line, which can be easily done. The operation will therefore in principle be precisely the same as that of justifying ordinary type, only that there can be no "overrunning." Each line must be justified by itself. The surplus letters rejected from use can be separated from

the rest by a quad temporarily inserted like the hyphen; then after the impression they may be cut off; or the matrix might be of the exact width of the column. The line of type having been justified, it is held firmly together at the sides, as by the nuts *i* in Fig. 13, or by other equivalent means more readily applied. It is then clamped firmly from above and below, and the material of which the matrix is to be made is pressed up against the line of type and the required impression obtained. Up to the present I have used the ordinary papier-maché matrix with good results. The impression being taken line by line (*i. e.*, not letter by letter) there is little fear of any distortion of one line by another.

By using wax, gutta-percha, or other suitable material for the matrix, a mold for electrotyping could be formed, and by inking the types and taking an impression on paper the impression could be transferred to stone or zinc and printed from in the usual way.

I claim—

1. In a type-writer or stereo-matrix machine, the combination, with a series of type-bars having a vertical row of type in an inverted position and arranged to move in vertical planes, a series of keys for positioning the type-bars to form a line of words, and a paper-carrier having a step-by-step movement, of mechanism such as described to impart to the paper-carrier a retrograde movement after each impression to bring the printed matter into view, and a mirror interposed between the type-bars, the paper-carrier, and the keys to expose the line of words on the type-bars to the view of the operator, substantially as described.

2. In a type-writer or stereo-matrix machine, the combination, with the printing-surface, of a paper-carriage movable toward and from the printing-surface and paper holding and feeding devices thereon, having an automatic forward movement to bring the paper to the printing-point on the carriage, and an automatic retrograde movement to expose it to the view of the operator, substantially as described.

3. In a type-writer or stereo-matrix machine, the combination, with the swinging paper-carriage, the paper-feeding roller provided with the ratchet and gear-wheel, and the pawl for rotating said roller to feed the paper, of a rack-bar engaging the gear-wheel to rotate the roller to bring the paper to the printing-point upon the forward movement of the carriage, and to rotate it in the opposite direction upon the return movement of the carriage to present the printed matter in view of the operator, substantially as described.

4. In a type-writer or stereo-matrix machine, the combination, with the type-bars having the type characters thereon, the paper-carriage and mechanism substantially such as described, whereby the printed matter is exposed to view immediately after the impression, of a mirror arranged below the carriage

whereby the characters on the type-bars in position to be printed at the subsequent impression may be inspected, substantially as described.

5. In a type-writer or stereo-matrix machine, the combination, with the sticker C, pins C⁴, and controlling-springs C⁵, of the rock-bars D, substantially as and for the purpose specified. 75

6. In a type-writer or stereo-matrix machine, the combination, with a key and a rock-bar D, of a sticker C, operated from said key and provided with diagonal slots C', a spring-controlled pin C⁴, and rods C² lying in said slots, 80 whereby as the sticker rises it is caused to recede, carrying the pins with it, substantially as and for the purpose specified.

7. In a type-writer or stereo-matrix machine, the combination, with the stickers C, having 85 a combined vertical and horizontal motion, as described, the spring-controlled pins C⁴, and shooting-bolts E, of the rock-bars D, substantially as and for the purpose specified.

8. In a type-writer or stereo-matrix machine, 90 the combination, with the rock-bars D, the shooting-bolts E, the perforated plate F, and pins F', of the interposed springs F², arranged and operating substantially as and for the purpose specified. 95

9. The combination, in a type-writer or stereo-matrix machine, of a vertically-moving type-bar and a stop-pin to limit the movement of the bar, with mechanism for positioning the pin, consisting of a sticker C, having a 100 compound vertical and horizontal movement and carrying a stop, a rock-bar operated by said stop on the sticker, and a shooting-bolt controlled by the rock-bar, substantially as and for the purpose specified. 105

10. In a type-writer or stereo-matrix machine, the combination, with the type-bars, the detent for holding said bars, and the pins for limiting the movement of the same, of the keys operating to project a pin and simultaneously release a bar to engage therewith, substantially as described. 110

11. The combination, in a type-writer or stereo-matrix machine, of a type-bar having a vertical movement, a detent for holding the 115 bar in a fixed position, and a traveler having a horizontal movement and engaging the detent to release the type-bar, substantially as and for the purpose specified.

12. The combination, in a type-writer or stereo-matrix machine, of a type-bar having a vertical movement, a detent to hold the bar in a fixed position, and a pin for limiting the movement of the bar and mechanism for releasing the bar from its fixed position and 125 positioning the same through the medium of the pin, which consists of a traveler moving at right angles to the movement of the bar and engaging the detent to release the bar, a shooting-bolt moving with the traveler and controlling the stop-pin, a rock-bar controlling the movement of the shooting-bolt, a key, and an intermediate connection, substantially as described, for operating the rock-bar when 130

- said key is depressed, substantially as and for the purpose specified.
13. In a type-writer or stereo-matrix machine, the combination, with a movable type-bar and a detent to lock said bar in position, of a traveler having the roller for engaging the detent to release the bar, substantially as described.
14. In a type-writer or stereo-matrix machine, the combination, with the movable type-bars, the detents to lock said bars in position, and the pins for arresting the movement of the bars when released, of the traveler engaging the detents to release the bars successively, the bolts mounted on the carriage for projecting the pins, and the keys for moving the bolts, substantially as described.
15. In a type-writer or stereo-matrix machine, the combination, with a type-bar having a vertical movement, a detent for holding the bar in a fixed position, and a stop for limiting the movement of the bar when released, of a spring-controlled traveler H, carrying a shooting-bolt that controls the limiting-stop, and a roller operating on the detent of the type-bar to release said bar, a ratchet and detent mechanism, and a key connected with and operating the detent to cause the traveler to move step by step under the stress of its spring, substantially as and for the purpose specified.
16. In a type-writer or stereo-matrix machine having the series of longitudinally-moving type-bars and pins for positioning the same, the combination, with a traveler H, moving transversely across the type-bars and provided with bolts for operating said pins, of ratchet-bars 1 and 3, and ratchet mechanism K K' K² K³ K⁴, substantially in the manner and for the purpose specified.
17. In a type-writer or stereo-matrix machine, the combination, with the type-bar, of flexible arms mounted thereon carrying the types at their outer ends, whereby the types may be deflected from normal position to form a correct line, substantially as described.
18. In a type-writer or stereo-matrix machine, the combination, with a type-bar, of an arm g, pivoted thereto and carrying the type at its outer end, and a flexible and extensible connection between said type and arm, substantially as and for the purpose specified.
19. In a type-writer or stereo-matrix machine, the combination of a series of pivoted type-carriers and types flexibly and extensibly connected therewith, whereby said types may all be brought to the same face-line and their heads arranged parallel to one another, the carriers being radially disposed, substantially as and for the purpose specified.
20. In a type-writer or stereo-matrix machine, the combination, with a series of type-carriers, of perforated type flexibly and extensibly connected with the carriers, and a tie-rod extending through and rigidly connecting the type together, substantially as and for the purpose specified.
21. In a type-writer or stereo-matrix machine, the combination, with type-bars, type-carriers pivoted thereto, and perforated type flexibly and extensibly connected with the carriers, of a tie-rod h for rigidly connecting the line of types, substantially as and for the purpose specified.
22. In a type-writer or stereo-matrix machine, as a means of flexibly and extensibly connecting the types c with the arms g, the combination therewith of the flat spring b and helical spring a, substantially as specified.
23. In a type-writer or stereo-matrix machine, the combination, with the type-bars, carriers mounted thereon, printing-type flexibly and extensibly mounted on said carriers, and elastic spaces interposed between said type, of a clamp engaging the type to compress the spaces and justify the line, substantially as described.
24. In a type-writer or stereo-matrix machine, the combination, with the type-bars, type-carriers pivoted thereto, perforated type flexibly and extensibly connected with the carriers, and elastic spaces interposed between said type, of a tie-rod h for rigidly connecting the line of types and compressing the spaces to justify the line, substantially as described.
25. In a type-writer, the combination, with a series of type-bars having a vertical movement, and mechanism, substantially as described, for positioning the bars to bring a given character thereon on a fixed line, of an inking mechanism consisting of inking-rolls supported from a yielding support, and a guide for guiding the rolls vertically, of the set line of type and a swinging frame having an arm that operates to move the inking-rolls over said line of type, substantially as and for the purpose specified.
26. In a type-writer, the combination, with a series of type-bars having a vertical movement, and mechanism, substantially as described, for positioning the bars to bring a given character thereon on a fixed line, of an inking mechanism consisting of inking-rolls supported from a yielding support, a guide for guiding the rolls vertically over the set line of type, a swinging frame carrying the material upon which the impression is taken, and an arm operating to move the inking-rolls over the line of type prior to the taking of the impression, substantially as and for the purpose specified.
27. In a type-writer, the combination, with a series of type-bars having a vertical movement, and mechanism, substantially as described, for positioning the bars to bring a given character thereon on a fixed line, of an inking mechanism consisting of inking-rolls supported from a yielding support, a guide for guiding the rolls vertically over the set line of type, a swinging frame for carrying the material upon which the impression is taken, a feeding mechanism, substantially as described, for intermittently feeding the ma-

terial, and an arm operating to move the inking-rolls over the line of type prior to the taking of an impression and after the material has been fed forward, substantially as and for the purpose specified.

28. In a type-writer, the combination, with a series of type-bars having a vertical movement, and mechanism, substantially as described, for positioning the bars to bring a given character thereon on a fixed line, of an inking mechanism consisting of inking-rolls supported from a yielding support, a guide for guiding the rolls vertically over the set line of type, a swinging frame carrying the material upon which the impression is taken, a feeding mechanism, substantially as set forth, for intermittently feeding the material, and a guard-plate pivoted near but eccentrically of the swinging frame and provided with an opening Q^2 , substantially as and for the purposes specified.

29. In a type-writer or stereo-matrix machine, the combination, with the type-bars, a series of keys for positioning the same to form a line of words, an intermittently-moving paper-carrier, and a guard or shield covering the side of the carrier which faces the type, said guard being provided with an opening for the passage of the line of type in taking an impression, of gearing operating to reverse the movement of the paper-carrier after an impression has been taken to move the printed line into position to be seen by the operator, substantially as and for the purpose specified.

30. In a type-writer or stereo-matrix machine, the combination, with the type-bars, keys for positioning the same to form a line of words, and a paper-carrier pivoted to oscillate or swing toward and from said line of words, of an operating-wheel, and a cord connecting said wheel with the pivoted paper-

carrier to move the same toward the line of type to take an impression therefrom, substantially as described.

31. In a type-writer or stereo-matrix machine, the combination, with the type-bars, keys to position the same to form a line of words, a paper-carrier pivoted to oscillate or swing toward and from the line of words, and a wheel for operating the paper-carrier, of inking-rolls having a motion across the face of the line of type controlled by the swinging paper-carrier, substantially as and for the purpose specified.

32. The combination, with the swinging frame N, its guard or shield Q^X , and the inking-rolls S, of an operating-wheel and intermediate connections such as described, whereby said swinging frame and its shield are moved forward and the inking-rolls are moved in a vertical direction, substantially as and for the purpose specified.

33. The combination, with a series of type-bars operated to move into given positions, the swinging frame N, carrying the paper upon which the impression is taken, the guard or shield Q^X , and inking-rolls for inking the type on the bars, of an operating-wheel and intermediate connections such as described, whereby on the rotation of the wheel the frame N is swung forward, the paper moved a certain distance, the inking-rolls moved over the type on the bars, and an impression therefrom taken on said paper, substantially as and for the purpose specified.

In testimony whereof I have hereunto set my hand in the presence of two subscribing witnesses.

EBENEZER WRIGHT.
